UNITED STATES PATENT OFFICE.

JAMES J. ESSEX, OF NEWPORT, RHODE ISLAND.

IMPROVEMENT IN SYRINGES.

Specification forming part of Letters Patent No. 70,540, dated November 5, 1867.

To all whom it may concern:

Be it known that I, JAMES J. ESSEX, of Newport, Newport county, Rhode Island, have invented a new and Improved Syringe; and I do hereby declare that the following is a full, clear, and exact description thereof, which will enable those skilled in the art to make and use the same, reference being had to the accompanying drawings, forming part of this specification.

This invention relates to a new and improved syringe which is applicable to all purposes for which a syringe is required, and which, consequently, I term a "universal syringe," it being capable of being used as an enemata apparatus or as a douche-syringe, and is portable and capable of being adapted for use in a moment of time.

My improved syringe is of the modern class in which the pump (cylinder and piston) is dispensed with, and an elastic bulb used instead.

The invention consists, first, in a receiver or reservoir provided with a glass or transparent plate, inserted in its side, so that when the device is used for enema-giving purposes a precise quantity of liquid may be used—to wit, a gill, pint, &c., as may be required; and this receiver or reservoir is designed to accompany the apparatus and form a part of the same.

The invention consists, second, in a rose or perforated nozzle, which I term a "douche," whereby wounds may be irrigated with a delicate spray of warm or cold water, as may be required. This device is also valuable for cleansing or washing the eyes.

The invention consists, third, in using, in connection with an elastic bulb as a suction and force pump, an elastic and a metallic tube, placed at or attached to opposite ends of the bulb, and using in connection therewith an air-chamber, all being arranged as herein fully shown and described, whereby a continuous stream may be thrown from the eduction-tube and the device adjusted to suit the various uses required of it.

The invention consists, fourth, in a novel and improved arrangement of packing, whereby perfectly-tight joints may be obtained.

In the accompanying sheet of drawings, Figure 1 is a view of my improved apparatus,

with the receiver and the connections in section; Fig. 2, a side view of the same with the parts differently arranged, but not in section; Figs. 3, 4, 5, 6, 7, 8, and 9, detached views of parts pertaining to the same.

Similar letters of reference indicate corresponding parts.

A represents a receiver or reservoir, which may be of metal, (block-tin would be a good material,) provided with a collar or nozzle, a, having an external screw-thread to receive a cap, b, through the center of which there is an opening for a pipe or tube, B, to pass, the latter extending down to the bottom of the receiver or reservoir, as shown clearly in Fig. 1. In the side of the receiver there is fitted, a plate of glass, A^x, or other transparent material, and the side of the receiver adjoining the transparent plate is graduated, so that any desired or given quantity of fluid may be placed within it. This is an important feature, as it enables injections to be given in accurate quantities, as a physician may prescribe. The side of this receiver or reservoir extends down below its bottom c, and the side below the bottom has a cover, d, fitted over it, forming a box, in which an elastic tube may be placed when not required for use.

The tube B has a female screw, d', cut in its upper end, to receive a small screw, e, of an elastic or metal tube, an elastic tube, C, being shown in Fig. 1, and in Fig. 2 the screw at one end of an elastic bulb, D, is shown. The tube B admits of the contents of the receiver A being entirely drawn or pumped out of it, the bulb D serving as a pump.

E is an air-chamber, which causes a continuous stream to be thrown or ejected from the bulb D, and in Fig. 2 this air-chamber is shown attached to the opposite end of the bulb D, and a flexible tube connected to the air-chamber. In Fig. 1 the bulb D is shown attached at one end to the elastic or flexible tube C, and the air-chamber attached to the opposite end, with a metallic tube, F, attached to the air-chamber, said tube F having the eduction-pipe G attached. This metallic tube F may be attached to the tube B in the receiver or reservoir, and one end of the bulb D attached to F, and the elastic tube C attached to the other end of the bulb.

The connections of these several parts may be varied at will, according as circumstances may require; but in all cases it is essential that a metallic or rigid part must be connected to one end of the bulb D, and an elastic tube to the opposite end; and in order to render the device applicable to all adjustments which may be required, curved and angular metal elbows E F may be used, as shown in Figs. 8 and 9.

In certain cases, when required, the flexible suction and the metallic discharge may be applied to one and the same end of the elastic bulb, as will be understood by referring to Fig. 1, in which the elastic or flexible suction is then attached to the air-chamber.

I would remark that valves f are employed (shown in Fig. 1) and applied in the different joints and connections, as may be required. Necessary valves are also employed in the air-chamber.

In order to render the connections or joints perfect, I have the male screw formed with a socket, g, in which the packing is placed, (see Fig. 1,) and this socket receives the end of the tube h, in which the female screw is cut. This socket prevents the packing from spreading laterally under the pressure, and causes a tight joint or connection; besides, the packing is totally concealed, and the joint or connection has a far neater appearance than when it is exposed, as in the old plan.

Figs. 4 and 5 represent what I term a "douche," which consists of a cap or nozzle, i, having a perforated plate, j, at its end. This perforated plate causes a fine spray to be ejected from the discharge-tube, and is extremely valuable for irrigating wounds, ulcers, or sores, and for washing the eye.

I would remark that eduction-pipes H H'

(see Figs. 6 and 7) may be used as circumstances may require, and these pipes attached either to the elastic tube or to the metallic one, whichever is used for the force or education.

Having thus described my invention, I claim as new and desire to secure by Letters Patent—

1. The employment or use, in connection with a syringe, of a receiver or reservoir, A, provided with a glass or other transparent plate, A^x, and with a screw-cap, b, and tube B, substantially as and for the purpose set forth.

2. The combination of a metallic and an elastic tube with an elastic bulb, when the former are attached to opposite ends of the latter, and used either in connection with or without an air-chamber, for the purpose specified.

3. The rose-nozzle or douche, composed of the cup i and perforated plate j, when used in connection or combined with a syringe provided with an elastic bulb, substantially as and for the purpose specified.

4. Providing the male screw of the connections or joints with a socket, g, to receive the packing, and prevent its lateral expansion under pressure where the two parts of the connection or joint are screwed together.

5. The arrangement of the rigid discharging-pipe and the flexible suction-tube and their valves at one end of the bulb, substantially as herein shown and described.

The above specification of my invention signed by me this 26th day of March, 1867.

JAMES J. ESSEX.
